UNITED STATES PATENT OFFICE

SIMON COOPER, OF BROOKLYN, NEW YORK

ELECTRICAL SOSTENUTO PIANO

Application filed March 25, 1927, Serial No. 178,211. Renewed September 10, 1930.

This invention relates to electrical sostenuto pianos, of the type wherein a current controller, as a pulsator or make and break device, is operated by string vibration to fluctuate a magnetic field, thereby in turn to sustain the vibration of said string as long as the circuit including the controller and electro-magnet is held closed.

One of the objects of the present invention is to provide an electrical sostenuto piano, wherein the volume of such a sustained string vibration may be varied by a single means, and preferably an electric one, to obtain a result during sostenuto equivalent to the result obtained in the ordinary piano by the use of the soft and loud pedals, that is, for varying the loudness of the sostenuto of all the strings sounding as a particular chord, regardless of which strings are thus sounded.

Another object is to provide an electrical sostenuto piano as just described, wherein the variable volume controls may be incorporated in a so-called player piano, and wherein, preferably, the bellows and perforate-web means common to most player-pianos may form parts of or coact with said controls.

Various other objects and advantages of the invention will be specifically pointed out or apparent hereinafter, in the course of a description of certain preferred embodiments of the various possible forms of the invention as shown in the accompanying drawing; it being understood, of course, that such forms are merely illustrative of combinations and arrangements of parts calculated to attain the objects of the invention, pursuant to present preference, and hence the detailed description of such forms now to be given is not to be taken as at all defining or limiting the invention itself. That is to say, the scope of protection contemplated is to be taken solely from the appended claims, interpreted as broadly as is consistent with the prior art, and with explanatory references to the specification only where a claim is ambiguous or to be impliedly limited beyond its express terms to avoid such art in order to save the validity of said claim.

In the accompanying drawing: Fig. 1 is a diagrammatic view of the invention as applied to an ordinary piano, showing a form of the invention wherein the key closes the sostenuto circuit and the 55 pedals are employed to interpolate various resistance elements in said circuit.

Fig. 2 illustrates a modification of the form of the invention shown in Fig. 1, in that the pedals are employed to vary the number 60 of electric battery cells in the circuit.

Fig. 3 is a diagrammatic view of the invention as applied to a player-piano of the pneumatic type, and showing a form of the invention wherein the sostenuto circuit is 65 closed by a key, said circuit is held closed by bellows, and another bellows arrangement varies the loudness of the tone by changing the number of battery cells in the circuit and by mechanically modifying the hammer action. 70

Fig. 3a shows in side elevation, on an enlarged scale, certain of the parts shown in side elevation in Fig. 3.

Fig. 3b is a section taken on the line 3b—3b 75 of Fig. 3a.

Fig. 3c is a section taken on line 3c—3c of Fig. 3b.

Fig. 4 is a diagrammatic view, based on the electrical arrangement of Fig. 1, showing 80 the electrical connections in multiple from the battery to the various circuit subdivisions corresponding to the different strings.

Fig. 5 illustrates a modification of the form of the invention shown in Fig. 3, in that 85 the bellows arrangement for varying the loudness of tone interpolates various resistance elements in the circuit.

In Fig. 1 as well as in Fig. 3, the piano string 10, stretched between the bridge-pieces 11 and 12, is provided with a sostenuto equipment including a magnet 13 in circuit with a pulsator 14 and a battery 15, such circuit including a normally open switch 16 adapted to be closed when a key 17 is depressed; the hammer being conventionally indicated at H and mounted in any well known manner such as is shown in the patent to Severy and Sinclair, No. 1,104,282.

In each of Figs. 1 and 2, the loud pedal is 100

conventionally indicated at L and the soft pedal is conventionally indicated at S. Each of these pedals carries an upstanding arm, this arm forming a part of the sostenuto circuit when its upper end is in contact with one of the buttons 20.

In Fig. 1 these buttons 20 form terminals for taps from different convolutions of the resistance coils 21 and 22; while in Fig. 2, 10 the buttons 20 form terminals for leads from different cells of the batteries 23 and 24, with one exception, to wit, that the button 20 to the extreme left in Fig. 2 forms the terminal for a lead cut into the circuit ahead of any 15 of the battery cells.

Further comparing Figs. 1 and 2, it will be noted that according to the arrangement of Fig. 1, where a variable resistance coil is controlled by the movement of a pedal, the 20 sostenuto circuit includes, in the order now to be stated, the upstanding arm of one pedal, one of the resistance coils, a connection 25, and the upstanding arm of the other pedal; and that according to the arrangement of 25 Fig. 2, where a variable voltage supplying element, or battery, is controlled by the movement of a pedal, the sostenuto circuit includes, in the order now to be stated, the upstanding arm of one pedal, a connection 26, 30 the upstanding arm of the other pedal, and the other battery.

With both pedals undepressed in Fig. 1, the sostenuto circuit, when closed at the switch 16, has a current traversing the same 35 of a strength equal to the E. M. F. of the battery 15 divided by the R of the circuit, which now includes the R of all the convolutions of resistance coil 21, resistance coil 22 being cut out of the circuit; while, with both pedals 40 undepressed in Fig. 2, the sostenuto circuit, when closed, has a current traversing the same of a strength measured by the E. M. F. of all the cells of the battery 24, all the cells of the battery 23 being cut out of the circuit. 45 Now, if the loud pedal of Fig. 1 be depressed all the way, all of resistance coil 21 as well as all of resistance coil 22 is cut out of the circuit, while if the loud pedal of Fig. 2 be depressed all the way, all the cells of the battery 23 as well as all the cells of the battery 24 become inserted in the circuit; and a fortissimo effect is secured. However, if the soft pedal of Fig. 1 be depressed all the way, both the resistance coils 21 and 22 will be 55 completely inserted in the circuit, while if the soft pedal of Fig. 2 be depressed all the way, only one of the cells of the two batteries 23 and 24 will be retained in the circuit; and a pianissimo effect is secured.

60 It will be noted that a plurality of the buttons 20 are provided in each case to coact with a loud pedal as well as a soft pedal; so that varying degrees of fortissimo and pianissimo may be obtained whenever required. 65 It will of course be understood that as pedal

L of Fig. 1 or 2 is more and more depressed, so as to contact with a button 20 further and further to the right in Fig. 1 or 2, the current strength in the sostenuto circuit will be more and more increased; and similarly, as the pedal S of Fig. 1 or 2 is more and more depressed, the current strength in the circuit will be more and more decreased.

It should be understood that the pedals L and S may be additional to the present foot 75 pedals. Also, obviously, equivalents of said pedals may be provided and located so as to be operated by the knee or hand of the performer. It will be further understood that, as an equivalent of the pedals L and S, there 80 could be provided a single see-saw pedal, one end for the loud and the other end for the soft tones.

As is well understood in piano actions, the ordinary loud pedal acts when depressed to 85 cause the dampers resting against the strings to clear away. Therefore, in employing a pedal or the like for varying degrees of fortissimo, as here, where the first smaller part 90 of the downward pedal movement is sufficient to bring in some fortissimo, it is desirable to arrange the piano-action connection so that the dampers will be cleared away from the strings at the very beginning of the 95 pedal depression.

Referring to Fig. 3, showing a form of player-piano installation according to the invention, it will be seen that the sostenuto circuit includes, in addition to the key-operated switch 16, an additional switch 27 100 connected by a rod 28 to a bellows 29. This latter switch is normally closed, and is provided that it may be opened at intervals during the playing of a given composition, to suspend the sostenuto action, thereby to obtain new musical effects or contrasts at different portions of the composition. In the case of a pneumatic player-piano, this switch 27 is conveniently operated from a perforation in the record-web; and so the bellows 29 110 is present as just stated, this bellows when expanded holding the switch 27 open and when exhausted permitting the upper spring member of the switch to close the same. It will of course be understood that pursuant 115 to this feature of the invention, a similar switch could be inserted in the circuit of Fig. 1, and associated with suitable means on the piano, say a key or pedal, to be set to permit such switch to open and stay open as long as 120 desired.

As to the normally open switch 16, this is shown in Fig. 3 as being closed directly by key depression, as in Fig. 1; but it may be explained that such switch 16 may desirably 125 be located so as to be actuated by the movement of the spindle (not shown) connecting the key with the hammer-action, or by the movement of the familiar bellows (not shown) operating said spindle.

The volume varying means of Fig. 3 includes the battery 15, a plurality of buttons 30 forming terminals for leads from various cells of the battery 15, and mechanical connections operated by a pair of bellows 31 and 32, certain of said connections selecting a button 30 and hence a predetermined number of the battery cells for interpolation in the circuit, and certain of said connections 10 acting to vary the hammer action mechanically.

Normally, the intermediate button 30 contacts the lower or swinging end of a switch-arm 33 to maintain some of the cells of the 15 battery, but less than all such cells, in the sostenuto circuit, as shown clearly in Fig. 3; this switch-arm being pivoted at 34.

The connections for operating the switch-arm 33, to swing the arm to contact the left 20 button 30, for pianissimo, or to swing the arm to contact the right button 30, for fortissimo, include a bell-crank 35, pivoted at 36, a link 37 joining the upstanding arm of the bell-crank and switch-arm 33, and a pair of 25 links 38 joining the other arm of the bell-crank with the two bellows 31 and 32. According to these connections, when bellows 31 is expanded and bellows 32 exhausted, the 30 switch-arm is thrown to contact the soft volume button 30 at the left; and when bellows 32 is expanded and bellows 31 exhausted, the switch-arm is thrown to contact the loud-button 30 at the right. To restore the switch-arm to contact the intermediate button 30, 35 both bellows are equally expanded, as by reducing the expansion of the previously expanded bellows 31 or 32 and by adding pressure to the previously exhausted bellows 31 or 32. Suitable perforations in the record-web 40 may be employed for thus controlling the bellows 31 and 32.

The connections for mechanically varying the hammer action here include means for varying the leverage of the hammer; and as 45 shown in Figs. 3, 6, 7, and 8, such means includes a shiftable hammer-fulcrum comprising a collar 39, slideable on the hammer-shank 46 and pivoted at 40 in the forward forked portion 41 of a carriage 42 riding on a guide-rod 50 43. Such carriage is shifted up or down from its normal intermediate position by a lever 44 pivoted at 45; one end of lever 44 coating with studs 46 on a rear-fin 47 on the carriage, and the other end of said lever connected to 55 the upper end of a link 48 the lower end of which is connected to one arm of a bell-crank 49. This bell-crank, which is pivoted at 50, has its other arm connected to switch-arm 33 by a link 51. It will be seen that when 60 the bellows 31 is expanded, for pianissimo as above, the carriage 42 is moved upward to reduce the leverage of the hammer; and when bellows 32 is expanded, for fortissimo, the carriage 42 is moved downward, to increase 65 the leverage of the hammer.

This hammer-action control, or an equivalent, may of course be incorporated in an electrical system for ordinary pianos pursuant to the present invention, as, for instance, in the system shown in Fig. 1, as by employing a 70 see-saw pedal as herein above referred to for both loud and soft effects and connecting one of the arms of said pedal to the lever 44 or an equivalent.

In Fig. 4, the different magnets are indicated at 13, each of which magnets, together with one of a plurality of pulsators each in a different circuit subdivision 13a, serve a particular string; such strings not being shown. In each of these circuit subdivisions is a 80 switch 16, normally open pursuant to the explanations hereinabove, so that as a particular key corresponding to a particular string is depressed, sostenuto is imparted to the vibration of that string. The circuit including these circuit subdivisions 13a has interposed therein a single switch 27 normally closed pursuant to the aforesaid explanations, so that whenever the sostenuto effect is to be suspended for an interval during the 85 playing of a musical composition the opening of said switch 27 makes such suspension complete as to all the springs. The control mechanism for loudness and softness of tone, is indicated merely, by the presence of the elements 15, 30 and 38 as in Fig. 3.

Referring finally to Fig. 5, there is shown the same battery 15 as in Figs. 3 and 4, but the buttons 30 are terminals for taps from different convolutions along the length of a resistance coil 52 in series with the battery 15. Then, a switch-arm similar to the switch-arm 33 may be connected as the latter is connected to a pair of bellows similar to the bellows 31 and 32; so that with both bellows expanded, the said arm contacts with the intermediate button 30 for ordinary volume, when one of the bellows is expanded said arm contacts with the button to the left for soft volume, and when the other bellows is expanded said arm contacts with the button to the right for 90 loud volume.

The arrangement indicated in Fig. 4, or an equivalent, is an important feature of the invention, as thereby the operations of all the magnets may be modified simultaneously and similarly by a single means or actuator.

Inasmuch as many changes could be made in the above constructions, and many apparently widely different embodiments of my invention could be made without departing from the scope thereof, it is intended that all matter contained in the above description or shown in the accompanying drawing shall be interpreted as illustrative and not in a 120 limiting sense.

It is also to be understood that the language contained in the following claims is intended to cover all the generic and specific features of the invention herein described and all state- 130

ments of the scope of the invention which, as a matter of language, might be said to fall therebetween.

What I claim is:

- 5 1. In the operation of electrical sostenuto installations for pianos of the type including electro-magnets and means acted on by string vibration to cause different magnets to vary their fields to sustain said vibration relative to different strings, the method which involves simultaneously and similarly varying the magnetic fields of all said magnets.
- 10 2. In the operation of electrical sostenuto apparatus for pianos of the type including electro-magnets for different strings or groups of strings, the method which involves providing a plurality of pulsators, arranging said pulsators so that different strings operate different pulsators, various magnets and pulsators being wired in series and such wirings being in parallel relative to a current source, whereby variation of a circuit element beyond said parallel wirings varies the magnetic field of all the magnets simultaneously and similarly, and providing such an element and varying the same for the purpose last mentioned.
- 15 3. In a piano, the combination of an electrical sostenuto equipment for the strings, and means for varying the sostenuto circuit relative to all the strings similarly while maintaining the resistance of said circuit substantially constant.
- 20 4. In a piano, the combination of an electrical sostenuto equipment for the strings, means for cutting in and out such sostenuto at will, and means for varying the output of current source for the sostenuto circuit at will during functioning of the sostenuto while maintaining the resistance of said circuit substantially constant.
- 25 5. The piano defined in claim 4, wherein the last-mentioned means includes a familiar actuating element of a piano, as a bellows in a player-piano.
- 30 6. In electrical sostenuto involving the use of a plurality of electro-magnets for a plurality of strings, the method of obtaining sound volume variations by affecting the operations of the magnets, which involves thus acting on all the magnets simultaneously, by a single circuit alteration while maintaining the resistance of said circuit substantially constant.
- 35 7. The method defined in claim 6, wherein said method involves making said single alteration by actuation of a familiar actuating element of a piano, as a pedal of an ordinary piano or a bellows of a player-piano.
- 40 8. In a piano, the combination of a vibratory string, electrical means for imparting sostenuto to said string, and means for varying such sostenuto at will to obtain varying volume while maintaining the total re-
- 45 sistance of said electrical means substantially constant.
- 90 9. In a piano, the combination of a vibratory string, and means for imparting electrical sostenuto to said string and for varying the effectiveness of the first-mentioned means while maintaining the resistance of said means substantially constant.
- 95 10. In a piano, the combination of a vibratory string, means for electrically imparting sostenuto to said string, said means including a current source and a circuit, and means for varying the loudness of the sostenuto while maintaining the strength of such source and the total resistance of said circuit both substantially constant.
- 100 11. In a piano, the combination of a vibratory string, means for imparting electrical sostenuto to said string, and means for varying the volume of such sostenuto, the last-mentioned means including a pneumatic instrumentality.
- 105 12. In a piano, the combination of an electrical sostenuto equipment for the strings, and pneumatic means for cutting in and out such sostenuto at will.
- 110 13. In a piano, the combination of a plurality of strings, separate means for each of certain of said strings for imparting sostenuto thereto, and means for rendering all said separate means inoperative simultaneously, at will.
- 115 14. In an electrical sostenuto piano, in combination with the strings, pulsators, sostenuto magnets, and a current source for the magnets, volume controls corresponding to the loud and soft pedals of an ordinary piano, and means by which actuation of one of said controls reduces current flow through the magnets and actuation of the other increases the flow.
- 120 15. In an electrical sostenuto piano, in combination with the strings, pulsators, sostenuto magnets, and a current source for the magnets, volume controls corresponding to the loud and soft pedals of an ordinary piano, and variable resistances in the magnet circuit, one controlled by one of said volume controls to reduce current flow and the other controlled by the other volume control to increase current flow.
- 125 16. In an electrical sostenuto piano, in combination with the strings, pulsators, sostenuto magnets, and volume controls corresponding to the loud and soft pedals of an ordinary piano, and a multi-cell battery as a source of current supply for the magnets, and sets of contacts connected to the battery in rheostat fashion, said volume controls having contact members to cooperate with the battery contacts to reduce or increase, respectively, current supplied to the magnets.

In testimony whereof I affix my signature.

SIMON COOPER. 120
